(57) CLAIM

I claim the ornamental design for a stackable beverage container, as shown and described.

DESCRIPTION

FIG. 1 is a top, front and right side perspective view of a stackable beverage container showing my new design;

FIG. 2 is a bottom, front and right side perspective view thereof;

FIG. 3 is a front devotional view thereof;

FIG. 4 is a side devotional view thereof, both sides being the same;

FIG. 5 is a rear elevational view thereof;

FIG. 6 is a top plan view thereof; and,

FIG. 7 is a bottom plan view thereof.
